UNITED STATES PATENT OFFICE.

ALBANO F. PEELMAN, OF ALBION, MICHIGAN.

MECHANIC'S CLAMP.

SPECIFICATION forming part of Letters Patent No. 781,356, dated January 31, 1905.

Application filed June 3, 1903. Serial No. 159,853.

To all whom it may concern:

Be it known that I, ALBANO F. PEELMAN, a citizen of the United States, residing at Albion, in the county of Calhoun and State of Michigan, have invented certain new and useful Improvements in Mechanics' Clamps, which are fully set forth in the following specification, reference being had to the accompanying drawings, forming a part hereof, and in which—

Figure 1 shows my said new device in side elevation in a work-bench and applied to work, having a fragment of the lower end of the stem broken away. Fig. 2 shows the stem *a* by itself, its front face turned toward the observer. Fig. 3 shows a fragment of the lower end of the clamp-stem holding a removable arm and stop therefor. Fig. 4 shows the arm shown in Fig. 3 in top or plan view on the cutting plane 4-4 of Fig. 3. Fig. 5 shows a cross-section of the stem *a* on the cutting plane 5-5 of Fig. 3.

Like reference-letters denote like parts throughout.

The object of my invention is to improve the construction of mechanics' clamps on the lines described and shown hereinafter.

A round rod *a* is provided on opposite sides with flat facets *a'*, which are inclined to each other toward the front at an angle, substantially as shown, ten or fifteen degrees, more or less. Between them and at the upper end of said rod or stem is a blade whose direction is central to said angle of the facets *a'* and whereof its front edge projects and is provided with a shelf or stop *b*, and directly back of said shelf is a pivot *c*, and slightly to the front from vertically over the fulcrum *c* is a fulcrum *e*. A crescent-shaped or curved arm *c* is slotted at one end to form two arms *c'*, which clasp the opposite sides of the blade *b* and turn on the pivot *c*. The free end of said arm *c* is also slotted, so as to form short arms *c*, which clasp the sides of a tenon *d*, forming a part of the presser or hand *d*, which is held to the arm *c* by the pin *d'* and which is limited in its motion on said pin by the top edges *d*, which are slightly inclined to each other and which strike against the straight face *c*, which forms the end of the slot be-

tween said arms *c*. Both near arms *c* and *c'* are shown removed to expose the mechanism behind them, as shown. The upper end of the slot between the arms *c* has a face or stop *c*, which contacts with the shelf or stop *b* when the arm *c* falls to the position indicated by the broken outline, which shows a fragment of said arm *c*. Said parts are so adjusted as to prevent the hand *d* from coming near enough to the stem to strike the user's hand clasping the stem *a*, which otherwise might be liable to happen, and thus produce severe injury. The stops *c* *b* being within the inside of the arms *c* cannot catch the hand should it be clasping that part of the device when the arm *c* is falling to its lowest position.

A spur *c* near the fulcrum *c* projects from the upper edge of the arm *c* and contacts with an eccentric *e*, turning on a pivot *e* in the upper end of the blade *b* by means of a lever-handle *e*, and forces said arm *c* into the position indicated by broken outlines and its hand *d* onto the material *f* (here representing fragments of two boards which are being glued together) to be pressed or held, the lever *e* being in this instance passed over into the position shown in broken outlines. The stem *a* is passed through a hole *i* in the bench *f*, which by reason of the one-sided pressure indicated by its position in the hole *i* will bind and hold with a firmness proportioned to the pressure.

To secure any fixed adjustment of the device, an adjustable stop *g* is slid on the stem *a* and fastened by a set-screw *g'* to any given place, and thereby holds the clamp at any desired height above the work-bench.

By adding a rigid arm *h* to the stem *a* opposite the arm *c* there is secured another form of mechanism for obtaining pressure. The arm *h* has an eye *h*, through which the rod *a* slides freely, and below said eye are opposed spurs *h*, forming a crotch *h*, the inner sides of which fit on the sides *a'* and bind to them with a force corresponding to the pressure on the platen or holder at *h* and also by means of the arrangement of said parts *a* and *h* hold said arm *h* in the same plane with the arm *c*. When the arm *h* is used, the stop *g* is placed under the eye *h* to hold the arm *h* in place.

from slipping off the stem *a*, as it would do when hit or raised but slightly from below under *h'*, because in that case the crotch *h'* would be released.

5 A clamp of this construction is readily adjusted and when desired permanently held to any particular adjustment, whereby it becomes an instrument of great expediency and of generally increased utility.

10 What I claim is—

1. The combination with a bifaceted stem, said facets converging, and said stem provided with an end blade, an arm on said blade a levered eccentric above and to actuate said

15 arm, of an arm provided with an eye and a crotch to fit said stem.

2. The combination with a bifaceted stem, said facets converging, and said stem provided with an end blade, an arm and a lever

on said blade, said lever to actuate said arm, 20 of an arm on said stem provided with an eye and a crotch to fit said stem.

3. The combination with a bifaceted stem, said facets converging, and said stem provided with an end blade, an arm, and a lever 25 to actuate said arm on said blade, of an arm on said stem with an eye and a crotch and a stop to said arm.

4. The combination with a stem having a blade at one end and a shelf on its edge, of a 30 slotted arm pivoted on said blade, provided with a stop projecting into said slot and contacting with said shelf.

ALBANO F. PEELMAN.
